AUTOMATIC TEMPERATURE CONTROL APPARATUS FOR HOT ROLLS

Ira Edward Smith, Stockton, Calif.

Application October 7, 1929, Serial No. 397,842

4 Claims. (Cl. 80—41)

This invention relates to the steel industry, and particularly to the hot rolls of rolling mills of various kinds, such as are used in forming relatively thin sheets from plates or bars. The present invention also particularly relates to the apparatus intended to be used in connection with the method of rolling mill operation, as far as the rolls are concerned, as set forth in my copending application for patent, Serial No. 397,255 filed October 10, 1929.

When the plates are passed through the rolls a very great friction is generated in the rolls and the temperature of the same tends to rise to a very high degree—a condition accentuated by the 15 heat of the metal being rolled. It has long been recognized that such excessive heat is something which should be avoided, since among other things it causes the rolls to rough up, warp and deteriorate, as well as causing the sheets when 20 rolled to be of uneven thicknesses. The rolls are therefore arranged with air and steam nozzle devices which are turned on to cause air and steam to be directed against the rolls when it is deemed necessary to reduce the temperature of the same. 25 The control devices at present are worked by hand, and the heat of the rolls both before and after the action of the cooling means is judged by the color of the rolls. This method is inaccurate and unsatisfactory, since the temperature 30 cannot thus be judged sufficiently close to enable the rolls to be maintained within close limits to that certain temperature (approximately 750° F. for steel rolling) which has been found to give the best results.

35 Unless the temperature of the rolls is maintained even however the rolls tend to gather and their rolling surfaces become unevenly spaced, and consequently the sheets are not rolled evenly. Also the sheets tend to become scaly. Other evils 40 also arise which are well known to those in the industry, and which heretofore have been considered unavoidable.

The principal object of my present invention 45 therefore is to avoid such evils by providing an apparatus arranged in connection with the rolls, and actuated by the heat of the rolls themselves, by means of which the temperature of the rolls is ordinarily maintained within very close limits to 50 a desired and predetermined degree of heat, without any attention on the part of the operator being necessary once the mechanism has been set for a certain given relative temperature.

55 A further object of the invention is to produce a simple and inexpensive device and yet one

which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Fig. 1 is a diagram showing my heat control apparatus arranged in connection with a pair of 65 rolls.

Fig. 2 is an enlarged end view showing the special mounting structure of the thermocouple.

Fig. 3 is a side view of the bracket member of 70 the supporting structure.

Referring now more particularly to the characters of reference on the drawing, the numeral 1 denotes the rolls of a rolling mill supported 75 in end frames 2.

Associated with the rolls and disposed on each 80 side of the lower roll are blow boxes 3 of standard character which are open to the atmosphere on their lower ends and toward the rolls on their upper ends, being positioned to blow air evenly over both rolls adjacent their meeting faces and 85 for substantially the full length thereof. Steam jet pipes 4 extend across the boxes and face toward the rolls so that when the steam is turned on a flow of air and steam is directed, on the principle of an injector, against the rolls to cool 90 the same. The use of these boxes is not new with me, but heretofore the steam has been turned on or off by hand, as the need for the same has been judged necessary by viewing the color of 95 the rolls, as set forth in the preamble. With my improved method of operation, however, I provide automatic control of the steam in the following manner:

The steam pipe 5 which is common to both jet 100 pipes has a normally closed needle valve 6 there-in whose opening is controlled by the energizing of a magnet 7, by means of suitable connections 8 extending therebetween. The type of valve and its controlling mechanism is preferably that which is fully shown and described in my Patent No. 1,594,021, dated July 27th, 1926, and hence a detailed description of the same is unnecessary here.

To cause the magnet to be energized and the valve to be opened only when the rolls attain a 105 certain predetermined temperature I use a thermocouple 9, the hot end of which engages one of the rolls centrally of its length. The ends of the thermocouple are connected to the millivoltmeter movement of a standard pyrometer con- 110

troller 10. The adjustable pointer 11 of this instrument is set along the scale of the same at the temperature at which it is desired to maintain the rolls (preferably 750° F.) and when the millivolt movement controlled pointer 12 reaches such temperature and engages the adjustable pointer, the circuit to the magnet is closed by the control mechanism of the instrument. This mechanism forms no part of my invention being, as stated, part of a standard instrument which may be purchased in the open market.

The hot end of the thermocouple engages the under surface of the lower roll centrally of its length, as stated, and is mounted in a particular manner so as to always bear evenly yet lightly against the roll as follows:

Secured to one of the end frames 2 in a suitable manner are vertically spaced vertical pins 13 on which a 90° angle bracket 14 is mounted 20 for swivel movement in a plane transversely of the roll.

A diagonal brace 15 connects the vertical and horizontal legs of the bracket, the latter being uppermost and somewhat close to the under 25 surface of the roll. The outer end of the bracket carries a saddle 16 which is swivelly mounted on a vertical axis. Swivelly mounted on a horizontal pin 17 supported by said saddle is a rigid bar 18 having an adjustable weight 19 mounted thereon toward one end, and a heat insulation block 20 of asbestos or the like on the other end and on which the hot end of the thermocouple rests. The thermocouple extends from said block toward the other end of the bar, and intermediate its ends is secured to the bar by suitable means, such as wrappings of tape, as indicated at 21. The thermocouple is flat in a horizontal plane at its hot end and is curved on the same radius as that of the roll so that the latter 40 will be engaged by said hot end for the full area of the same. A transversely extending brace rod 22 is adjustably connected at one end to the bracket 15 and at its other end to a support 23 secured to the frame 2. In this manner the bracket is held rigid while being capable of initial 45 adjustment so as to push the thermocouple just where it is needed—preferably close to the vertical center line of the roll and so that its curved hot end bears properly against the face of the roll. This arrangement also enables the bracket to be easily swung to one side and out of the way when the device is not in use, as when the rolls are being removed or replaced after 50 repolishing or refinishing operations.

The length of the horizontal arm of the bracket is substantially that of one half the length of the roll, the swivel mounting of the saddle which supports the thermocouple-supporting bar enabling the latter to adjustably engage the roll midway of its length—a position which I have found to be the most efficient and advantageous. The weighted bar on which the thermocouple is directly mounted causes the latter to bear against the roll with a constant pressure at all times, so that there is never any air gap between the roll and thermocouple to interfere with the direct and unbroken transmission of heat from one to the other. At the same time the pressure of the thermocouple against the roll is not sufficient to cause undue wear of the thermocouple to be had.

In operation therefore the heat of the rolls is directly transmitted to the thermocouple and

thence to the pyrometer. As long as the temperature of 750° F. (or to whatever temperature the pointer 11 has been set) is maintained, the valve magnet remains deenergized and the steam valve remains closed, as previously stated.

When however the temperature rises to any appreciable extent above this point the magnet becomes energized by the action of the pyrometer as controlled by the thermocouple; the steam valve is opened and steam and air are therefore directed through the boxes 3 against the rolls to cool the same. As soon as the normal heat of the rolls is regained, which heat will of course be transmitted through the thermocouple to the pyrometer, the steam valve will be again closed.

From the foregoing description it will be readily seen that I have produced such a device as substantially fulfills the objects of the invention as set forth herein.

While this specification sets forth in detail the present and preferred construction of the device, still in practice such deviation from such detail may be resorted to as do not appear from a departure from the spirit of the invention, as defined by the appended claims.

Having thus described my invention what I claim as new and useful and desire to secure by Letters Patent is:

1. In an automatic heat control apparatus for hot-rolls, a thermocouple disposed under one of the rolls, a substantially horizontal bar pivoted intermediate its ends at a fixed point relative to the rolls and on which the thermocouple is mounted with its hot end adjacent one end of the bar and positioned to contact with the roll, a weight on the bar toward its opposite end, roll cooling means and means actuated by a predetermined heat in the thermocouple for then causing the cooling means to function.

2. A structure as in claim 1 with a heat insulation block secured to the bar and on which the hot end of the thermocouple rests.

3. In an automatic heat control apparatus for hot-rolls, roll cooling means, a bracket under the lower roll, means supporting said bracket for horizontal swivel movement transversely of the roll, adjustable brace means for holding the bracket against such movement, a bar pivoted in connection with the bracket for swivel movement in a vertical plane, a thermocouple mounted on the bar and having its hot end adjacent one end of said bar to engage the under surface of the adjacent roll and means actuated by a predetermined heat in the thermocouple to place the cooling means in operation.

4. In an automatic heat control apparatus for hot-rolls, roll cooling means, a bracket under the lower roll, means supporting said bracket for horizontal swivel movement transversely of the roll, means for adjusting and holding the bracket in a fixed position, a saddle swivelly mounted on the outer end of the bracket for movement about a vertical axis, a bar pivoted intermediate its ends in the saddle for movement in a vertical plane, a thermocouple mounted on the bar with its hot end adjacent one end of the same to contact with the face of the adjacent roll, a weight on the bar toward its opposite end and means actuated by a predetermined heat in the thermocouple to place the cooling means in operation.
